UNITED STATES PATENT OFFICE.

MALCOLM WRIGHT AND HENRY BECKER, OF BALTIMORE, MARYLAND.

SAFETY AND SIGNAL DEVICE.

Application filed March 28, 1921. Serial No. 456,447.

To all whom it may concern:

Be it known that we, MALCOLM WRIGHT and HENRY BECKER, citizens of the United States, residing at Baltimore, in the county 5 of Baltimore City and State of Maryland, have invented certain new and useful Improvements in Safety and Signal Devices; and we do hereby declare the following to be a full, clear, and exact description of the 10 invention, such as will enable others skilled in the art to which it appertains to make and use the same.

This invention relates to a device for cutting off the flow of steam to a turbine or 15 other steam engine when certain conditions arise making it necessary or desirable that the flow of steam be cut off promptly to avoid damage to the machinery. The invention has been primarily designed for use in 20 connection with a turbine-driven pump, the apparatus being controlled by the water which is pumped by the turbine.

The various features of novelty and invention will appear from the detailed 25 description taken in connection with the accompanying drawings forming part of the specification.

In the drawings,

Figure 1 is a diagram illustrating our improved safety and signalling device arranged 30 for operating the throttle valve, vacuum breaker and signal;

Figure 2 is a detailed enlarged view of the connection to the throttle valve, showing 35 the same in its open position in full lines and in a closed position in dotted lines;

Figure 3 is a transverse sectional view of a shaft showing a modified form of the invention as applied to the shaft of the 40 circulating pump and adapted to operate a circuit closure for automatically cutting off the motive power should the pump fail to work, and

Figure 4 is a top plan view of one of the 45 movable rollers used in the construction shown in Figure 3.

In the drawings, S indicates a steam main supplying power to a prime mover, as a turbine, for actuating a pump for forcing water 50 through a pipe line 1. In connection with the pipe line is a sleeve or casing 2 within which is a plunger or float 3 having a stem 4 which carries a switch element 5 of a switch X, 6 indicating the other elements of 55 the switch which latter elements are suitably secured to a support 8 having binding posts

9 for receiving wires 10 and 11. Wire 11 connects to a solenoid, the return wire being indicated at 13 which is connected to a suitable source of electric energy B as is also wire 60 10. When the switch X is closed, as occurs when there is not a predetermined amount of water flowing in the pipe 1, the solenoid is energized by the battery B.

Extending from the solenoid is a frame 65 14 to which is pivoted, as at 16, a lever, the arms thereof being indicated by 15 and 15'. Extending from the core of the solenoid is a post 17 to which said lever is pivotally connected as at 17'. When the solenoid is energized the post 17 thereof moves upwardly, consequently the lever is swung about its pivot 16.

Connected to the lever arm 15' is a link 18 which connects to throttle-closing mechanism now to be described. In the steam main S is a throttle of which 23 indicates the casing. The stem of the throttle is indicated at 23^a and passes through the bottom of the casing in a conventional manner. After 75 fixed to the throttle stem is a yoke 23^b and, turnably mounted in the lower end of the yoke is the terminal end of a throttle-adjusting screw 25 having a hand wheel 23'. This screw passes through a screw block 25' 80 which is slidably mounted in a sleeve a of a frame A depending from the valve casing 23. The screw block is provided with trunnions 27 which extend through slots 30 in opposite sides of the sleeve a. It will now be 85 seen that the block 25' has a range of up and down movement commensurate with the length of the slot 30 and, inasmuch as the throttle within the casing 23 is connected to said block through the yoke 23^b, the throttle 90 will partake of the same movement as said block. When the trunnions 27 are at the upper end of the slot, the throttle is open. To 95 close the throttle quickly the screw block is allowed to drop, which results in a sudden 100 closing of the throttle.

The mechanism for holding said block in elevated position and for allowing it to drop will now be described. Mounted on each trunnion is a lever 26 which at one end is 105 anchored to the frame A by a link 28. The free ends of levers 26 are bridged by pin 31 which is adapted to be engaged by hook 32. When the hook is disengaged from the pin there is nothing to sustain the screw block 25' in elevated position and, consequently, it moves downward with a resultant

closing of the throttle, the lever 26 then assuming the position shown in dotted lines in Fig. 2.

The hook 32 is keyed to shaft 24 which is turnably mounted in brackets 36 extending laterally from the frame A. Also keyed on the shaft 24 on an end thereof projecting beyond the bracket 36 is a hand lever 19. When the handle end of said lever is moved 10 in a clockwise direction, the hook 32 is disengaged from the pin 31 thus allowing the screw block 25' to drop, as will now be readily understood.

The hook 32 is disposed between the brackets 36 and has two radially projecting fingers 33 and 42. Finger 33 is designed to abut the frame A to prevent the lever 19 and hook from swinging too far in a counter-clockwise direction after the hook has been 20 disengaged from the pin.

The finger 42 of said hook is adapted to be pressed upon by a trip-finger 43 affixed to a shaft 37 bridging the ends of brackets 36. Affixed to one end of shaft 37 is a crank arm 35 to which is connected a link 34 which leads to governing mechanism not shown nor necessary to be described. When the arm 35 swings in a counter-clockwise direction, the trip-finger 43 will press upon the 30 finger 42 of said hook to disengage the latter from the pin 31 and, consequently, screw block 25' will drop, as will now be understood.

Also affixed to shaft 37 and disposed between the brackets 36 is an upwardly extending arm 41 (preferably a pair of them, one on either side of the finger 43) which is pressed upon by spring 40 held in operative relation therewith by means of a link 39 anchored to the frame A. The spring 40 will cause the trip-finger 43 to trip the hook 32 but is normally restrained from doing so by link 34 which, as already indicated, is connected to governing apparatus which is designed to release link 34 only under certain conditions.

It will now be seen that hook 32 can be tripped by hand lever 19 and also by spring 40 when link 34 is released to permit said spring to act. The third means for tripping the hook will now be described. Lever 19 is provided with an extension 19'. To this extension, link 18 is connected, this link being connected, as will be recalled, to the arm 15 of the solenoid-operated lever. Downward pull on link 18 will disengage hook 32 from pin 31 as will now be readily understood.

Connected with the arm 15 of the solenoid-operated lever is a valve mechanism known 60 as a vacuum breaker which is so constructed that when a latch 46 is released, the valve mechanism will be operated by the action of a spring. Latch 46 is connected to the arm 15 of said lever by link 45. After the vacuum breaker has been operated or tripped

by latch 46 it can be reset by hand lever 49 through mechanism not necessary to be described.

Mounted on the steam line S is a whistle 48, the lever 48' of which is actuatable by solenoid 50 which is connected by wires 51 to wires 11 and 13. When the switch X is closed, the solenoid will be energized to pull the whistle lever whereupon the whistle will be sounded, thus giving notice that the apparatus is not functioning normally.

Instead of employing plunger or float 3 in connection with the pipe line 1 for closing the switch X, means of the type illustrated in Fig. 3 may be employed. In this view 54 indicates a shaft of a circular water pump. Affixed to this shaft is a two-part ring 55 having radial lugs 57 to which are pivoted arms 59 each having a roller 62 at their free ends. 53 is a two-part annular casing surrounding the arm-provided ring 55. At the top of the casing is mounted a vertically movable slide-segment 64 having a stem 65 on which is affixed a switch element 5' for contacting with switch elements 6', these switch elements corresponding to the switch elements 5 and 6 Fig. 1.

When the shaft 54 is rotating, and consequently when the pump is functioning, the centrifugal force will swing the arms 59 outwardly and thus exert outward pressure on slide-segment 64 sufficient to open the switch X. Should the pump cease to function or slow down in speed, and thus not pump sufficient water, the slide-segment 64 will approach the ring 55 and consequently the switch X will close the circuit between wires 10 and 11, consequently current will flow through the circuit to energize the solenoid 12 and also the solenoid 50.

The operation of the above described mechanism may be briefly stated as follows:

When the pump is pumping sufficient water through the pipe line 1, the plunger 3 will be maintained in such position by the pressure of the water that the switch X will be open. However, should there not be sufficient water flowing in the pipe line 1 for one reason or another, the float will drop to close the switch X whereupon the circuit in connection with battery B will be closed thus allowing the solenoid 12 to be energized. It may be stated at this point that within the casing 2 may be provided means for controlling the degree of sensitivity of the plunger 3. When the solenoid 12 is energized, link 18 will be pulled downward thus disengaging hook 32 from pin 31 to allow the throttle to drop to closed position. Movement of the solenoid-operated lever will also cause the latch 46 of the vacuum breaker to be tripped thus completely throwing the turbine apparatus and hence preventing damage to said apparatus. If the turbine should rotate at too high speed, the

governing mechanism to which link 34 is connected will release said link 34, whereupon the spring 40 will operate to trip the hook 32, whereupon the throttle will close, thus cutting off steam to the turbine. If it is desired to quickly close the throttle by hand, hand lever 19 can be operated to trip the hook 32 and also the vacuum breaker.

We claim:

1. The combination with a steam main supplying power to a prime mover and a conduit for receiving fluid pumped by the prime mover, of a solenoid, means controlled by the fluid in the conduit for energizing the solenoid, a throttle in the steam main, a trip holding the throttle open, and means actuated by the solenoid for tripping the trip to quickly close the throttle.

2. The combination with a steam main supplying power to a prime mover and a conduit for receiving fluid pumped by the prime mover, of a solenoid, means controlled by the fluid in the conduit for energizing the solenoid, a throttle tending to close by gravity, a trip holding the throttle in open position and means operated by the solenoid for tripping the trip when the solenoid is energized.

3. The combination with a gravity actuated steam throttle, a frame, a block slidable in said frame, means connecting said block to the throttle, a lever anchored at one end to the frame, means connecting the lever to the block, a hook swingably mounted on the frame, means on the lever for engagement with the hook, and means for disengaging the hook from the lever, comprising a lever mounted on said frame.

4. The combination with a gravity actuated steam throttle, a frame, a block slidable

in said frame, means connecting said block to the throttle, a lever anchored at one end to the frame, means connecting the lever to the block, a hook swingably mounted on the frame, means on the lever for engagement with the hook, a lever fixedly connected to said hook, and means for swinging the last-mentioned lever to trip the hook.

5. The combination with a gravity actuated steam throttle, a frame, a block slid- 50 able in said frame, means connecting said block to the throttle, a lever anchored at one end to the frame, means connecting the lever to the block, a hook swingably mounted on the frame, means on the lever for en- 55 gagement with the hook, a lever fixedly connected to said hook, means connected to the lever for swinging the same to trip the hook, and a bell-crank lever supported on the frame for tripping the hook.

6. The combination with a steam main supplying power to a prime mover, a pipe line through which water is pumped by the prime mover, and a vacuum breaker, of a solenoid, a lever movable by the solenoid, 65 a connection between the lever and vacuum breaker for actuating the latter when the solenoid is energized to move said lever, a throttle in said steam main, a connection be- 70 tween the throttle and said lever, for actu- ating throttle closing means when said lever is moved, an electric circuit for the solenoid, and a switch in said circuit responsive to the fluid in the pipe line, said solenoid being energized when said switch is closed.

In testimony whereof we affix our signatures.

MALCOLM WRIGHT.
HENRY BECKER.
